UNITED STATES PATENT OFFICE

AXEL G. GULBRANSEN, OF RIVER FOREST, ILLINOIS, ASSIGNOR TO GULBRANSEN COMPANY, OF CHICAGO, ILLINOIS, A CORPORATION OF ILLINOIS

PLAYER PIANO

Application filed January 24, 1927. Serial No. 163,016.

This invention relates to player pianos, and more particularly to that class of player pianos in which the action is exhausted by pedal operated bellows or equivalent means.

5 My invention relates primarily to means for operating the roll motor independently of the power unit for exhausting the action. By providing power operated means for driving the roll motor I reduce the volume of air 10 which has to be handled by the pedal operated means fifty per cent or more, greatly decreasing the effort required in operating the pedals and giving much quicker and more accurate control of the expression. A further 15 important feature of my invention is the provision of novel means for easily and accurately controlling the operation of the roll motor exhausting means. Further advantages and 20 objects of my invention will appear from the detailed description.

In the drawings:—

Figure 1 is a front view of a player piano of known construction, with the front boards of the case removed, showing my invention as 25 applied;

Fig. 2 is a diagrammatic view illustrating the independence between the roll motor exhausting means and the action exhausting means;

30 Fig. 3 is a section through the throat of the motor tension reservoir;

Fig. 4 is a diagrammatic view, partly in perspective, of the connections between the re-roll lever and the shift lever, illustrating 35 the motor control; and

Fig. 5 is a detail, partly in section, illustrating the exhaust motor control switch and the arm for operating the same on the re-roll lever shaft.

40 The player piano illustrated is of known construction and includes the action of known type which includes the pneumatic stack or wind chest 1 upon which are mounted the striker pneumatics, as usual. This

45 pneumatic stack is connected by tube 2 to throat 3 of the power unit 4. This unit includes equalizers 5 and bellows 6, the bellows being operated by pedals 7 connected thereto in a known manner.

50 The spool box 8 is mounted on a shelf

bracket 9 supported above the stack 1. Roll chucks 10 and 11, together with the tracker bar 12 and spool 13 are mounted in the box 8. The chuck 10 and spool 13 have driving connections with a roll motor 14, which is 55 pneumatically operated and is of known construction, through suitable driving connections including a shift lever which controls the operating connections between the motor and the spool and chuck for winding the music sheet 16 off of the roll 17 on to spool 13, or vice versa for re-winding the roll.

The throat 3 of unit 4 is provided at the end thereof adjacent tube 2, with a gate valve (not shown) which is operated in a known 60 manner by means of pneumatic 18 controlled by a valve which is connected by tube 19 to a silence control valve 20 mounted on the under-face of bracket shelf 9. This valve is normally closed but may be opened by means 65 of a button 21 extending through bracket shelf 9 and is also opened automatically by a pin 22 carried by shift lever 23 and disposed for contact with the inclined lower face of head 24 of the valve structure. When the 70 valve 20 is opened atmospheric air is admitted through the tube 19 connecting the pneumatic 18 to the equalizer 5 thus collapsing the pneumatic and through the connections 25 closing the gate valve. This cuts off communication between the throat of the unit 4 and the other parts of the action communicating therewith in such manner as to eliminate possibility of playing of any note during re-winding of the roll. Gate valves and means 75 for operating the same, controlled by a silence control valve, for rewinding, are well known in the art. An arrangement of the throat, gate valves, and associated parts similar to that above described is disclosed in my patent 80 for player piano, Number 1,563,977, issued December 1, 1925.

The player piano so far described is of well-known construction in this art and the various mechanisms operate in the usual 85 manner. The present practice is to connect the roll motor 14 to the power unit 4 so as to be exhausted thereby, a suitable governor and tempo valve being provided for regulating the speed of the motor and varying the 90 100

tempo. With the motor connected to the power unit an unnecessarily large volume of air has to be handled which renders operation of the pedals tiresome and does not give the 5 same easy and delicate control of the expression as can be obtained by reducing this air volume. In player pianos in which the action is exhausted manually, as by the pedal operated means referred to, the expression 10 can be varied at the will of the player by increasing or decreasing the rapidity of operation of the pedals thus correspondingly increasing or diminishing the air tension in the action system. In this respect the manually 15 operated player piano has a very distinct advantage over the so-called reproducer piano in which all parts are operated by power and a special expression device is provided which automatically varies the expression in accordance 20 with perforations of the music sheet. This feature of the reproducer player piano is objectionable as the player has no control whatever over the expression and the individuality of the player does not enter at 25 all into the rendition of the selection played. For this reason many persons prefer the manually operated type of player piano even though this necessitates operation of the 30 pedals. By providing means for operating the roll motor independently of the action exhausting means, this objection is avoided and, as previously noted, the volume of air handled is reduced by at least fifty per cent, greatly increasing the ease with which the 35 pedals are operated and also giving a more delicate control of the expression.

I provide a suitable device in the nature of a pump or exhauster for exhausting the motor independently of the action exhausting 40 means. In the particular form illustrated this device consists of an exhaust fan 25 which is secured upon armature shaft 26 of an electric motor 27 of suitable type. This fan operates in a casing 28 the intake of 45 which is connected by a tube 29 to a tension reservoir 30. This reservoir is provided at one end with a throat 31 divided by a partition 32 (Fig. 3) into two chambers 33 and 34. Chamber 33 has direct communication with 50 reservoir 30 by a duct 35 and chamber 34 is connected by a tube 36 to the exhaust of motor 14. Partition 32 is provided with an opening 37 which is normally closed by a gate valve 38. This gate valve is operated by a 55 pneumatic 39 connected by link 40 to crank 39^b of the valve rod 39^a, to be moved into open position when the pneumatic is collapsed. Communication between this pneumatic and throat 31 is controlled by a valve 60 which is actuated by atmospheric pressure admitted through a tube 41 which communicates with the silence control valve 20. The tension reservoir has associated therewith a governor 42 and a tempo valve 43 mounted 65 on the throat 31, this valve and the governor

being both of known type. The tempo valve is connected to the tempo lever 44 by an adjustable connecting rod 45 and is operated in the usual manner to control the speed of the motor. A governor and tempo valve and associated parts arranged and related as above set forth are disclosed in my Patent 1,563,977 previously referred to, and are now well known in the art. When rewinding the music roll, the silence control valve 20 is 70 opened so as to close the gate valve of the bellows throat 3 and open the gate valve 38 of the tension reservoir throat 31. This admits air directly from the tube 36 into the reservoir 30 by means of the opening 37 and the duct 35, cutting out the governor 42 and the valve 43 so that the motor 14 is operated at high speed when rewinding the music sheet. 75

It will be seen that by this arrangement the means for operating the roll motor is entirely separate and independent from the exhausting means and the volume of air to be handled is reduced by at least fifty per cent greatly increasing the ease of operation of the action 80 exhausting means and also giving a very accurate and delicate control of the expression. It will also be noted that the motor can be readily controlled in the same manner and by the same means as is employed for this purpose in the present type of player piano in which the motor is exhausted by the same means as is employed for exhausting the action. 95

Operation of the electric motor 27, and the 100 driving connections between the roll motor 14 and the spool 13 and roll chuck 10, are controlled by the re-roll lever 46 which is supported on the key bed 47 adjacent the tempo lever 44. The key bed also supports the key lock lever and the sustaining and melody levers which are mounted thereon in their usual positions. Lever 46 is secured to one end of a shaft 47' lockably mounted on the under face of the key bed in the usual 105 manner. This shaft is provided with a depending arm 48 to which is secured one end of a rod 49 the other end of which is pivoted to an arm 50 at the lower end of a vertical shaft 51 which is rockably mounted adjacent 110 one end of the player piano case. This shaft is provided at its upper end with an arm 52 connected by a rod 53 to the lower end of shift lever 23. This connection between the re-roll lever and the shift lever is, broadly, 115 very commonly employed in player pianos but has been varied by a provision of a special connection between the rod 53 and the lower end of lever 23. The shift lever is provided at its lower end with a horizontally 120 elongated head 54 having a slot 55 for reception of the outwardly bent end portion of rod 53. This bent portion or finger 56 of the rod is normally held at the left hand end (as 125 considered in Fig. 4) of slot 55 by a tension 130

spring 57 connecting lever 23 and rod 53. This connection permits movement of the re-roll lever 46 in a clockwise direction beyond that required to move the shift lever 5 23 into roll rewinding position.

A control switch 58 of known type is connected in series in the circuit of motor 27. This switch includes an "on" push button 59 and an "off" push button 60. These buttons 10 tons are disposed to be operated by two integrally connected arms 61 and 62, respectively, secured to shaft 47 and disposed transversely thereof. The angular relation between the arms 61 and 62 is such that when 15 the shaft 47 is turned to full re-wind position the arm 62 is out of contact with button 60. After the music sheet has been completely rewound the lever 46 is turned into its extreme position in clockwise direction thus 20 bringing the arm 62 into contact with button 60 and depressing this button so as to open the switch and stop the motor. In starting to play the lever 46 is turned in a counter-clockwise direction into playing position, in 25 the usual manner, shifting the shift lever 23 into playing position, at which time button 59 is depressed by arm 61 to close the circuit setting motor 27 into operation. While other means may be provided for controlling the 30 electric motor 27 and the roll motor, I prefer to employ the means illustrated and above described as this conforms more closely to the standard practice and permits the use of the levers now commonly used in player 35 pianos for this purpose.

What I claim is:—

1. In a player piano, music roll unwinding and rewinding means, pedal operated wind chest exhausting means, and power means for 40 operating said unwinding and rewinding means, said operating means being independent of the wind chest exhausting means during operation of said unwinding and rewinding means in unwinding direction.

45 2. In a player piano, music roll unwinding and rewinding means including a roll motor, pedal operated wind chest exhausting means, and power operated means for exhausting the roll motor, the motor exhausting 50 means being independent of said wind chest exhausting means during operation of the unwinding and rewinding means in unwinding direction.

55 3. In a player piano, music roll unwinding and rewinding means including a roll motor, wind chest exhausting means, and means for exhausting the roll motor, the motor exhausting means being independent of the wind chest exhausting means during operation of 60 the unwinding and rewinding means in unwinding direction.

65 4. In a player piano, music roll unwinding and rewinding means including a roll motor, wind chest exhausting means, and power operated pumping means connected to the roll

motor, said pumping means being independent of the wind chest exhausting means during operation of the unwinding and rewinding means in unwinding direction.

5. In a player piano, music roll unwinding 70 and rewinding means including a roll motor provided with an exhaust, pedal operated wind chest exhausting means, an exhauster having its intake connected to the roll motor exhaust, and a motor driving said exhauster, the exhauster being independent of the wind chest exhausting means during operation of the unwinding and rewinding means in unwinding direction.

6. In a player piano, music roll unwinding 80 and rewinding means including a roll motor provided with an exhaust, pedal operated wind chest exhausting means, an exhaust fan having its intake connected to the roll motor exhaust, and a motor driving said fan, the 85 fan being independent of the wind chest exhausting means during operation of the unwinding and rewinding means in unwinding direction.

7. In a player piano, music roll unwinding 90 and rewinding means including a roll motor, pedal operated wind chest exhausting means, and power means for operating the roll motor simultaneously with and independently of the operation of the wind chest exhausting 95 means during operation of the unwinding and rewinding means in unwinding direction.

In witness whereof, I hereunder subscribe my name this 19th day of January, 1927.
